UNITED STATES PATENT OFFICE

PHILIP S. CASE, OF NIAGARA FALLS, NEW YORK, ASSIGNOR TO ELECTRO METALLURGICAL COMPANY, A CORPORATION OF WEST VIRGINIA

SPRAY PRODUCING DEVICE

Application filed February 8, 1929. Serial No. 338,587.

My invention relates to spraying devices and especially to such devices wherein air under pressure is used to project subdivided solid material at a comparatively low velocity and to control the mixing of liquids with the solids so as to produce coatings of liquid impregnated solids.

It is among the objects of my invention to separately project a mixture of air and powdered solid, a mixture of air and liquid binder and a current of air from the device and to form a moistened composition outside of the device.

Another object of my invention is to project the moistened solids against the object to be coated at such a low velocity that fragile parts of the object may be coated without being injuriously affected by the force of the projected material.

Another object of my invention is to produce a thorough moistening of the powder exterior of the device and at the same time to control the character of the coating produced as well as increase and decrease the rate of deposition.

My invention may be embodied in devices which are used to produce coatings of metal powders on sand casting molds. The accompanying drawings illustrate such a device in which

Fig. 1 is a diagrammatic view of the air, powder and binder supply system,

Fig. 2 is a longitudinal sectional view of a spray gun,

Fig. 3 is an enlarged longitudinal sectional view of the nozzle of the spray gun shown in Fig. 2,

Fig. 4 is a view in side elevation of the air distributing ring,

Fig. 5 is a view partially in cross-section of the air distributing ring taken along the line V—V of Fig. 4,

Fig. 6 is a view in side elevation of the emulsifier ring,

Fig. 7 is a view partially in cross-section of the emulsifier ring taken along the line VII—VII of Fig. 6,

Fig. 8 is a view in side elevation of the nipple member,

Fig. 9 is an end elevational view of the nipple member shown in Fig. 8,

Fig. 10 is a sectional view of the nipple member taken along the line X—X of Fig. 9, and

Fig. 11 is a cross sectional view of the air and powder mixer.

The device consists broadly of means to mix powdered solids and air, means to emulsify liquid binder and air, means to equalize the pressure of air and the air and binder mixture, and means to combine the said mixtures and to produce a low nozzle velocity of the mixtures which are mingled at points external of the nozzle.

The air is supplied through a main high pressure conduit 1, as shown in Figure 1, which is connected to a source of air under pressure such as the compressed air tank 2. The pressure of the air in tank 2 may be reduced to the maximum working pressure through a reducing valve 3. The air is supplied from the main line 1 through branch pipes 4 and 5 to the powdered metal and liquid containers respectively and to the head of the spray gun through a pipe 6 which may be provided with an air regulating valve 7 mounted either on the spray gun assembly or near the branch pipes 4 and 5.

The branch pipe 4 leads to the powder reservoir 10 through a pressure reducing valve 11. A branch 12 in pipe 4 conducts air around the reservoir through a nozzle (b) in the dust mixer 13 so that the same relative fluctuations in the air pressure are communicated to the powdered metal in the chamber of the reservoir 10 and to the dust mixer 13.

The metal powder flows through the connection 15 around the end of nozzle (b) as shown in Fig. 11 where it is picked up by the air, atomized and carried forward into the pipe 16 which is attached to the mixer by appropriate connections. The nozzle or orifice tube (b) is carried by an adjusting nipple (d). The adjusting nipple (d) is provided with a slot (e) in which a screw driver can be inserted to screw the nipple back and forth to vary the supply of metal powder.

In order to produce a uniform continuous supply of mixed powder and air at a low

velocity, it has been found necessary to have an air pressure on the solids in tank 10 sufficient to force them around and in front of the nozzle (b) and to employ the air discharged from the nozzle merely as a mixing, atomizing, and propelling agent after the solids are delivered to the end of the nozzle. To obtain this action means are provided in the by-pass 12 to restrict the by-pass so that 10 a lower pressure of air will be delivered to the mixer 13 than to the tank 10. The valve 14 in by-pass 12 is a convenient means of producing the restriction and the valve has the further advantage of being adjustable so 15 that various conditions of air supply for the jet may be arranged, but other means to restrict and regulate the by-pass 12 may be used.

Within certain limits the differences in 20 fineness or density of the powder and variations in air supply pressure may be compensated for by adjusting the valve 14, but all sizes of powder cannot be atomized with the best results into a low velocity stream 25 with a given nozzle adjustment. With finer powders the nozzle usually operates best when the tip is positioned well beyond the entrance of branch 5' but the nozzle may be adjusted back for coarser powders by turning 30 the nipple (d).

Longer jets and smaller openings around the nozzle may be used with free flowing powders while a larger or smaller jet may be used to increase or decrease the volume of 35 air and the initial jet velocity. Good atomization at low velocity has been obtained with ferro-chrome powder which was ground to pass a screen of 30 meshes to the inch and retained on a screen of 60 meshes to the inch 40 with the following nozzle and adjustments: a one eighth inch diameter jet (b), and an annular spacing of one quarter inch between the walls of the nozzle and mixer with the nozzle projected entirely across a one half 45 inch diameter solids-pipe 5'. With a more dense powder, ferro-tungsten of the same fineness, a shorter jet gave about the same results. Free flowing powders and lower density solids generally require a smaller pressure 50 in the tank 10 so as to propel them around the nozzle while more dense solids require more violent atomizing conditions at the jet. I make the proper variations by means 55 of the valve 14 in by-pass 12, by interchanging larger and smaller jets and by varying the projection of the nozzle across the branch 5'.

An air relief valve 17 in the top of the 60 tank 10 is used to start and stop the flow of metal powder to the dust mixer 13. To start the dust mixer the valves 11 and 14 are opened. Valve 17 is then closed and the dust is forced down through the pipe 15 picked-up by the air issuing from nozzle (b) and carried in a cloud into the pipe 16. The amount

of air admitted to the mixer 13 and the velocity of the mixture delivered by the mixer is regulated by opening the valve 14 more or less. The mixer is stopped merely by opening the valve 17. This relieves the pressure of the air in the tank 10 and stops the flow of dry powder. The flow of air through the by-pass 12 and mixer 13 is usually continued at least until all the powder is discharged from the pipe 16. In order at all 75 times to have a small amount of air passing through the by-pass 12 and pipe 16, I may put an auxiliary by-pass around valve 11 and regulate the valve 18 therein so that a 80 small leakage of air will always exist from the main supply through the conduit 16.

The branch pipe 5 leads to the top of a container 20 which holds a supply of liquid binder. A by-pass 21 from the branch pipe 5 conducts air to the liquid mixer at a pressure and with the same pressure fluctuations as those prevailing in the tank 20. A pressure reducing valve 22 is connected in the pipe 21 to roughly regulate the supply of air to the liquid mixer 23. Liquid is supplied to the mixer from the bottom of tank 20 through the valve 24 and pipe 25. The liquid mixer 23 may be connected under or near the tank 20 as shown in broken lines in Figure 1, but good results are obtained when it is assembled on the handle of the spray gun. When the liquid mixer is assembled on the spray gun flexible conduits are preferably used instead of rigid pipes 21 and 25 to conduct liquid and air to the mixing device.

The liquid mixer 23 is preferably embodied in the spray gun and consists of an extension 26 of the liquid pipe 25 which is arranged to discharge into an extension of the air pipe 21 at an angle of about 30°. A brace 30 is provided between pipes 21 and 26 to strengthen the device. Valves 32 and 31 in the air and liquid pipes regulate the supply of air and binder respectively. The mixer 23 is a preliminary mixer for the binder, its function being to produce a regulated supply of air mixed with a constant regulated supply of liquid binder and to project the mixture into the passage 33 which is connected through the handle of the gun to a passage 51 in the gun head.

The spray gun shown in Figures 2 and 3 consists further of a handle portion which may be formed around an enlarged central pipe 35 carrying a bracket 36. The bracket 36 is provided with openings through which the binder mixture pipe 33 and the air pipe 6 are passed. Pipes 6 and 33 may be fitted on one end with unions 6' and 33' so that they 125 may be readily disconnected. The forward ends of these pipes are connected to a support 34 through nipples 37 and 38, and the spray gun head 39 is secured to the plate 34 by a plurality of screws 40. The central pipe 130

35 is connected to the support 34 through a nipple 41 and at its other end is provided a reducer 42 to which the dust mixture pipe 16 is attached.

5 A mixture of air and metal dust is extremely abrasive and will grind away a metal conduit at a rapid rate. I have found that this mixture can be successfully transported in pipes which have a lining of resilient plastic material. For the best results I use a gum rubber hose 43 as a lining for the pipe 35. The rubber hose 43 is extended through the central opening in the gun head and terminates in the exit nozzle 52. The hose 43 is 10 passed through the gun head and pipe 35 and the inner end of the hose is forced over a short frusto-conically shaped ferrule 44 which expands the end of the hose. The extended end of the hose bears against the end 15 of the pipe 35 and against the reducer 42 which holds it in place when the reducer is screwed down.

The spray gun consists of a handle having the passage 50 for air, a passage 51 for 25 mixed binder and air, and a passage 53 for mixed dry powder and air. The passage 53 in the gun head is disposed axially in the head so that a mixture of powder and air will be discharged from port 52 in a central 30 stream.

In the gun head, the air passage 50 and the passage 51 for mixed liquid and air extend lengthwise of the nozzle. The extreme end of the head is cut away, so as to form sections 35 severally cutting across passages 50 and 51. Reduced cylindrical sections and shoulders are formed in this operation so that suitable fitting pieces and collars may be attached and chambers formed for mounting the various 40 parts of the equalizer for the air and the emulsifier for the air and binder mixture.

The air passage 50 opens into a circular chamber 60 Figure 3 which is formed by cutting a circular groove in the shoulder 61. The larger reduced barrel portion of the head is threaded and a flat perforated ring 62 is screwed on the reduced portion to form the forward wall of the air chamber 60. The flat ring 62 may have small equally spaced 45 perforations 63 around its entire circumference but I prefer to leave unperforated a segment 64 which may subtend an angle of about 30° at the center of the ring. The unperforated portion of the ring is spaced 50 opposite the passage 50 and serves as a baffle upon which the air impinges and then passes around the chamber 60 and equalizes to some extent through the perforations 63. A nipple member 65 having a beveled portion 66 is screwed on this reduced portion and forms another annular chamber 71. The nipple 65 is reduced at its forward end to a section 67 which extends beyond the barrel portion 68 of the gun head. The nipple 65 is locked 65 by a cap 70 which is threaded on the gun

head 39 and bears against the forward end of the nipple. The partially equalized air issues through the openings 63 in the ring 62 into air chamber 71 which is formed between the ring 62, the beveled edge 66 of the 70 nipple 65 and a wall of the cap 70.

The air is again and more completely equalized by passing it around the nipple member 65 next to the inner wall of the cap 70. The passage between the cap and the nipple member may be a narrow circular space or grooves 75 may be cut across the face of the nipple member 65. The grooves 75 are preferably spirally disposed and direct the air tangentially into an annular chamber 76 which is 80 formed between the reduced end 67 of the nipple 65 and the end wall of the cap 70. The chamber 76 is preferably of sufficient depth to give a considerable free space in which the air from the grooves 75 may be 85 swirled and caused to cut across the small openings 78 which are spaced around the circumference of the reduced part 67 and direct the air so as to agitate the stream of air and metal powder issuing from the passage 52. 90

The direction of the air issuing from the openings 78 may be made to change the character of the spray accordingly as the air is directed perpendicularly, or obliquely, to the axis of the powder mixture. Obliquity of the air jets may be obtained by advancing the fitting piece 67 so that the jets 78 will be obstructed more or less by the end of the barrel. 95

The orifices 78 may be directed tangentially toward the current of metal and air which issues from the exit 52 in order to give a swirling motion or they may be directed radially at an angle to the axis of the passage 53. I prefer to space the small orifices 78 100 equally and to direct them radially and perpendicularly to the axis of the passage 53. The pressure of the air which is discharged through the orifices 78 is equalized and the jets constitute a screen of air through which the liquid binder and metal powder mixture 105 passes and they are subjected to violent agitation.

The mixture of air and liquid binder which is formed in the mixer 23 is conducted through the passage 51 and discharged into an annular chamber 85 of the emulsifier. The chamber 85 is formed between the shoulder 86 of the head 39 and a collar 87 which is given a sliding fit on the reduced portion 88 of the head. 110

The collar 87 is grooved on its flat faces. These grooves 89 and 89' as shown in Figures 6 and 7 may be inclined to the radii of the collar or they may be cut radially on the face of the collar. I prefer to cut the grooves 115 radially in a staggered relation to each other in the opposite faces of the collar as shown in Figure 6. This arrangement helps to disperse the air throughout the liquid and to form an emulsion as the mixture passes 120 130

through the grooves 89 across the edge of the collar in a spiral direction and then through the grooves 89'. The collar 87 is slightly smaller than the threaded bore of the fitting piece 65 and an annular passage between the fitting piece having a corrugated wall is formed by the threaded bore. The threads also serve to disperse the air in the liquid during its passage across the face of the collar 87.

The face 90 of the nipple member 65 forms the outer wall of a passage which conducts the emulsion to the exit orifices 91 which are spaced around the reduced part 88. The orifices 91 are formed by boring the fitting piece 65 so as to slidably fit over the part 88 and then grooves 91 are cut in the inner face of the fitting piece. These grooves preferably traverse the inner face of the fitting piece 65 parallel to the axis of the gun head but they may be cut along other lines, as for example, spirals. I prefer to make the exterior of the barrel 88 and the interior of the nipple cylindrical and to cut a large number of grooves 91 in the part 67 and to provide means so as to give the jets of emulsion an impulse which will converge the jets. A groove 93 having an arcuate cross-section is cut around the barrel 88 for this purpose. The nipple member 65 with its grooves 91 extends beyond the tip of the barrel 88 and the orifices 78 for the air, are located beyond the end of the barrel so that the envelope of binder will be discharged from the orifices 91 and converge toward the stream of metal powder and the air which is discharged from port 52.

In operation, the mixture of powder and air is made in the mixer 13, conducted through the pipe 16 and discharged from the gun through passage 52 in a constant regulated stream. Liquid binder is supplied in regulated quantity from the tank 20 through passage 25 to the mixer 23 and mixed with the desired quantity of air which is supplied through passage 21. The discharge from the mixer 23 is a stream of binder interspersed with air. This is broken up, homogenized or emulsified and equalized in the emulsifier in the head of the spray gun and the emulsion is discharged through the passages 91 in a plurality of fine jets which form a cylindrical envelope around the air and powder discharge. The air is conducted through passages 6 and 50, and the air equalizer in the gun head, and is discharged through the ports 78 so as to violently agitate the air and powder mixture after it issues from the nozzle. The violently agitated mixture of the air and powder mixture almost instantly picks up the envelope of liquid binder and absorbs the liquid, so that at a short distance from the nozzle, a composite jet of uniformly moistened powder suspended in air is formed. The velocity of the stream of mois-

tended powder, its wetness and its dilution with air may be regulated by admitting more or less air and liquid binder to the system. For coating sand molds, the stream of moistened powder is projected against the surface of the mold where it forms a more or less porous coating depending on the wetness of the powder, the degree of compactness of the powder, and the size of the solid particles.

It is evident that various modifications of the device described may be made without departing from the spirit of my invention. Therefore, I do not wish to be understood as limiting my invention except by the prior art and by the invention as defined in the claims annexed hereto.

I claim as my invention:

1. In a device for producing a spray of gas, liquid and solids, a source of gas under pressure, a container for comminuted solids, a container for liquid, mixers for solid and gas and for liquid and gas, a conduit for the solid and gas mixture having a discharge orifice, a conduit adapted to discharge the mixture of liquid and gases in an envelope around the discharged solid and gas mixture and a conduit for gas having orifices to project the gas into the discharged mixture of solid and gas, a communication for conducting gas from said source to said solids container, a by-pass around said solids container connecting said communication and the solids mixer and a valve in the solids container to relieve the air pressure therein and stop the flow of solids.

2. A device for producing a spray of gas, liquid and solids which comprises a source of gas under pressure, means to mix gas and solids, means to mix liquid and gas, passage means to conduct gas and said mixtures to discharge orifices, the means for conducting and discharging the liquid and gas mixture including a head portion having bores, said head having a reduced portion, a nipple member attached to said head having a recessed portion adapted to form a chamber around said body communicating with one of said bores, a ring member in said chamber for forming a tortuous passage therein, said reduced portion and nipple forming a discharge passage which communicates with the chamber.

3. A device for producing a spray of gas and liquid-moistened solids which comprises a source of gas under pressure, means to mix gas and solids, means to mix liquid and gas, passage means to conduct gas and said mixtures to discharge orifices, the means for conducting and discharging the liquid and gas mixture including a head having bores, said head having a reduced portion, a nipple member attached to said head having a recessed portion adapted to form a chamber around said body communicating with one of said bores.

bores, a ring member in said chamber for forming a tortuous passage therein, said ring having grooves on its flat faces, said body and nipple forming a discharge passage which 5 communicates with the chamber.

4. A device for producing a spray of gas and liquid-moistened solids which comprises a source of gas under pressure, means to mix gas and solids, means to mix liquid and gas, 10 passage means to conduct gas and said mixtures to discharge orifices, the means for conducting the liquid and gas mixture including a head having bores, a reduced portion in said head, a nipple member attached to said 15 head having a recessed portion adapted to form a chamber around said body communicating with one of said bores, an obstruction in said chamber forming a tortuous passage therein, said nipple having an inner bore with 20 grooves which communicate with said chamber and form discharge passages between the nipple and the reduced portion of the body.

5. A device for producing a spray of gas and liquid-moistened solids which comprises 25 a source of gas under pressure, means to mix gas and solids, means to mix liquid and gas, passage means to conduct gas and said mixtures to discharge orifices, the means to conduct gas including a head having bores, a 30 cap for said head, a reduced portion on said head, a recessed nipple member on said reduced portion forming an intermediate chamber communicating with one of said bores, a discharge chamber, said intermediate chamber 35 having a perforated member to distribute gas therein and said nipple having discharge orifices communicating with the discharge chamber.

6. A device for producing a spray of gas 40 and liquid-moistening solids which comprises a source of gas under pressure, means to mix gas and solids, means to mix liquid and gas, passage means to conduct gas and said mixtures to discharge orifices, the means to conduct gas including a head having bores, a 45 cap for said head, a reduced portion on said head, a recessed nipple member on said head forming with said cap an intermediate chamber communicating with one of said bores 50 and a discharge chamber, said nipple having grooves in its outer surface to provide passages between the chambers and ports to conduct air from the discharge chamber.

7. A device for producing a spray of gas 55 and liquid-moistened solids which comprises a source of gas under pressure, means to mix gas and solids, means to mix liquid and gas, passage means to conduct gas and said mixtures to discharge orifices, the means 60 to conduct gas including a head having bores, a cap for said head, a reduced portion on said head, a recessed nipple member on said head forming with said cap an intermediate chamber communicating 65 with one of said bores and a discharge cham-

ber, said nipple having spiral grooves in its outer surface to provide passages between the chambers and ports to project air from the discharge chamber transversely of the discharged mixture of solids and air.

8. A device for producing a spray of gas and liquid-moistened solids which comprises a source of gas under pressure, means to mix gas and solids, means to mix liquid and gas, 70 passage means to conduct gas and said mixtures to discharge orifices, the means to conduct gas including a head having bores, a cap for said head, a reduced portion of said head, a recessed nipple member on said head forming with said cap an intermediate chamber communicating with one of said bores and a discharge chamber, said nipple having grooves in one portion thereof to provide communication between the chambers and to produce agitation of air in the discharge chamber and ports to project air from the discharge chamber in a direction perpendicular to the axis of the bore for the solids and gas mixture.

9. A device for producing a spray of solids, liquid and gas which comprises a spray gun adapted to combine constituents of said spray, a mixer for solids and gas, a reservoir for subdivided solids, a conduit for supplying gas to the reservoir at a predetermined pressure to expel solids therefrom and a pipe to conduct solids to the mixer; a by-pass connecting said conduit and mixer, and adjustable means to regulate the gas in the by-pass so as to supply gas to the mixer at a lower pressure than said predetermined pressure.

10. A device for producing a spray of solids, liquid and gas which comprises a spray gun adapted to combine constituents of said spray, a mixer for solids and gas, a reservoir for subdivided solids, a conduit connecting said reservoir with a source of pressure-gas, so as to expel solids from the reservoir with a pressure reducing valve in said conduit to supply gas to the reservoir at a predetermined pressure, said mixer being below said reservoir so as to receive the expelled solids, a by-pass leading to said mixer and connected between said reducing valve and reservoir, means in said by-pass to supply gas to the mixer at a lower pressure than said predetermined pressure, a by-pass around said reducing valve to provide a leak between the pressure source and the mixer, and means to conduct the mixture of solids and gas to the spray gun head.

11. A device for producing a spray of solids, liquid and gas which comprises a spray gun adapted to combine constituents of said spray, a mixer for solids and gas, a reservoir for subdivided solids, means to supply gas pressure to said reservoir, means to supply gas to said mixer at a lower pressure than the gas in the reservoir, a liquid reservoir con-

- 5 nected to a source of gas under pressure, a mixer for liquid and gas connected to said gas-source and to said liquid reservoir, a pressure reducing valve between the liquid mixer and the source of gas and means to conduct mixed solids and gas and mixed liquid and gas to the spray gun head.
- 10 12. A device for producing a spray of solids, liquid and gas which comprises a spray gun adapted to combine constituents of said spray, a mixer for solids and gas, a reservoir for subdivided solids, means to supply gas pressure to said reservoir, means to supply gas to said mixer at a lower pressure than the gas in the reservoir, a liquid reservoir connected to a source of gas under pressure, a mixer for liquid and gas connected to said gas-source, and to said liquid reservoir, means to regulate the flow of liquid supplied to said liquid mixer, a pressure reducing valve between the liquid mixer and the source of gas, and means to conduct mixed solids and gas and mixed liquid and gas to the spray gun head.
- 15 13. A device for producing a spray of solids, liquid and gas which comprises a spray gun head adapted to combine the constituents of said spray, a source of pressure gas, a main gas connection between said source and the spray gun head, a liquid and gas mixer having a connection with said spray gun head and including a liquid reservoir adapted to be subjected to a high pressure of gas, means to mix liquid under pressure with gas at a pressure lower than that obtaining in said main gas connection or reservoir, a solid and gas mixer having a connection with the spray gun head, a reservoir for solids adapted to be subjected to a lower pressure than said liquid reservoir or said main gas connection, a connection between the mixer and solids reservoir, a connection on the solids mixer with a gas pressure supply which gives a lower pressure than that obtained in said solids reservoir and a nozzle in said solids mixer adapted to commingle the solids and gas whereby a low velocity current of mixed powder and gas may be delivered.
- 20 14. A device for producing a spray of solids, liquid and gas which comprises a spray gun head, a source of gas under pressure, a reservoir for solids, a reservoir for liquid, means to impress gas pressure on the solids in said solids reservoir, means to mix said solids with gas at a lower pressure than that impressed upon the reservoir whereby a low velocity current of mixed solids and gas is delivered to the spray gun head, a mixer for liquid and gas having a gas connection with the source of gas, means to deliver liquid from said reservoir to the liquid mixer at a higher pressure than the gas delivered thereto, whereby a mixture of liquid and gas
- 25 is delivered to the spray gun head, a gas con-

nnection between the source of gas and the spray gun head capable of delivering gas at a pressure higher than the gas delivered to either of said mixers, means in said spray gun to discharge the mixture of liquid and gas as an envelope around a central spray of solids and gas and means to inject the gas into the central spray of solids and gas at an angle to the axis thereof.

70 15. The combination with means to provide a low velocity current of mixed solids and gas, means to provide a current of mixed liquid and gas and means to provide a current of gas, of a device to project said currents and combine the same external of said device which comprises a spray gun head having longitudinally arranged passages to conduct said gas and said mixture separately through the head, means in the air conducting passage to equally distribute the air angularly around said head, a fitting piece on said head having air discharge ports directed at an angle to the axis of the head and communicating with the air passage.

75 16. A device for producing a spray of 90 solids which comprises a reservoir for subdivided solids, a mixer having a chamber communicating with the solids reservoir, a connection adapted to supply gas under pressure to the contents of said reservoir, a gas 95 connection on the mixer having means adapted to supply gas thereto at a lower pressure than that supplied to the contents of the reservoir, said gas connection including a removable nozzle which extends into said chamber, 100 means to mount the nozzle so as to immerse it with solids under pressure and to adjust the extension of the nozzle into said chamber, and means to conduct mixed solids and gas from the chamber.

105 17. A device for producing a spray of solids which comprises a reservoir for subdivided solids, a tubular mixer having a chamber and side connection communicating with the solids reservoir, a connection adapted to supply gas under pressure to the contents of the reservoir, a gas connection on the mixer adapted to supply gas thereto at a lower pressure than that supplied to the contents of the reservoir, said gas connection 110 on the mixer having an axially disposed nozzle which is adapted to be immersed with solids under pressure and means communicating with said chamber to conduct mixed solids and gas from the mixer.

115 In testimony whereof, I affix my signature.
PHILIP S. CASE.
